UNITED STATES PATENT OFFICE.

ABRAHAM SHUMAN, OF BOSTON, MASSACHUSETTS.

DESIGN FOR A BUTTON.

SPECIFICATION forming part of Design No. 25,136, dated February 11, 1896.

Application filed December 12, 1895. Serial No. 571,949. Term of patent 7 years.

To all whom it may concern:

Be it known that I, ABRAHAM SHUMAN, a citizen of the United States, residing at Boston, in the county of Suffolk and State of Massachusetts, have invented and produced a new and original Design for Lapel-Buttons, of which the following is a specification, reference being had to the accompanying drawings, forming a part thereof, in which—

Figure 1 is a plan; Fig. 2, a side elevation, and Fig. 3 a bottom view showing my design.

The leading feature of the design consists in the circular button having its face formed in two equal sections colored buff and blue, respectively.

A is the button-head, which is of circular

contour, with its face formed in two sections, A' A², of contrasting colors. In actual use this surface ornamentation is in the "buff and blue" of the "Continental Army," and the button is designed to be worn on patriotic occasions, or days commemorative of the brave deeds of the Continental Army, and thereby assist in keeping alive the spirit of patriotism. 25

What is claimed is—

The design for a lapel-button, as shown and described.

ABRAHAM SHUMAN.
